UNITED STATES PATENT OFFICE.

STANLEY ROKOSZ, OF HAZLETON, PENNSYLVANIA.

CURTAIN-STRETCHER.

1,232,979.

Specification of Letters Patent. Patented July 10, 1917.

Application filed May 26, 1914. Serial No. 841,090.

To all whom it may concern:

Be it known that I, STANLEY ROKOSZ, a citizen of the United States, residing at Hazleton, in the county of Luzerne and State 5 of Pennsylvania, have invented new and useful Improvements in Curtain-Stretchers, of which the following is a specification.

This invention relates to curtain stretchers and one of the principal objects of the device 10 is the provision of a stretcher in which curtains of various sizes may be securely fastened upon the frame so that they can be dried without wrinkles or creases.

Another object of the invention is the provision 15 of a stretcher having all the parts detachable or pivotally connected together so that they may be conveniently folded into compact form for storage or shipment.

Another object of the invention is the provision 20 of a stretcher having side, end and bracing members capable of considerable adjustment for the purpose of accommodating the device to different size curtains.

Further objects of the invention will appear 25 as the following description is read in connection with the accompanying drawing, which forms a part of this application, and in which:

Figure 1 is a perspective view of the device 30 set up for operation.

Fig. 2 is a vertical transverse sectional view taken approximately on the line 2—2 of Fig. 1.

Fig. 3 is a detail longitudinal sectional view taken on the line 3—3 of Fig. 1.

Fig. 4 is an enlarged transverse sectional view taken on the line 4—4 of Fig. 1.

Fig. 5 is a perspective view of the device 40 partially folded.

Fig. 6 is a similar view of the device completely folded.

In the specific embodiment of the invention as illustrated herein the stretcher comprises side members 1 and 2 and end members 45 3 and 4 and a bracing member 5. The bracing member 5 is constructed in two parts 6 and 7, the former being provided with a dove-tail channel 8 adapted to receive the member 7 which is constructed to 50 form with the channel and has connected to its inner end a spring locking pawl 9 arranged to engage apertures 10 in the base of the channel 8 so as to hold the two members 6 and 7 in adjusted position. The outer 55 end of the member 7 has secured thereto a block 11 whose upper surface is flush or in

a plane with the upper surface of the side member 1. This block has pivoted to it the separate sections of the side member 2 which are indicated at 2^a and 2^b while the member 6 60 6 has pivoted thereto the separate sections of the side member 1 indicated at 1^a and 1^b. Each of the sections 1^a, 1^b, 2^a and 2^b are constructed in a similar manner, as shown in Fig. 4, of two parts one slidably mounted 65 upon the other and specifically indicated by the reference characters 12 and 13. The part 12 of each section carries a dove-tail rib 14 which enters a dove-tail channel 15 on the part 13. The parts 12 and 13 are 70 held in adjusted position by means of pawls 14' which engage apertures 15' formed in the parts 12, the pawls being pivoted to the parts 13.

The parts 12 and 13 are each provided 75 with a plurality of pins 16 and 17, the former being in the shape of upright penetrating members spaced a suitable distance apart on the parts 12 and the latter being in L form having upright penetrating portions 80 and are carried by the parts 13.

The end members 3 and 4 are pivotally connected to the outer ends of the parts 13 of the sections 2^a and 2^b and are constructed 85 of separate sections 3^a and 3^b, the former having a dove-tailed rod 18 secured thereto arranged to engage in a dove-tail channel formed in the part 3^b. The sections of the end members are held in adjusted position by pawls 19 which engage apertures 20 in 90 the parts 3^a, the pawls being pivoted to the side edges of the parts 3^b. Each part 3^b has its free terminal provided with a shoulder 21 to abut against the free terminal end of one of the parts 13 and if desired a fastening device may be applied at its end to removably join the parts 3^b and 13. Each of the end members has hooks or penetrating pins 22 and 23 similarly applied to their respective parts as described for the side 95 members 1 and 2 and each part 3^a of said end members has pivotally secured thereto the bracing or supporting legs 23' which are adapted to fold into parallelism with the end members, as shown. Each of the 100 parts 12 of the sections 1^a, 1^b, 2^a and 2^b of the side members 1 and 2 have their inner corners rounded, as shown at 24, so as to permit folding of the parts, as will be hereinafter described.

In folding the device from the position 110 of the parts as shown in Fig. 1 the sections

1^a and 1^b are folded upon the brace 5 with their ends abutting the block 11. The bracing or supporting legs 23' are then folded upon the end members and the end members in turn folded upon the sections 2^a and 2^b which are then folded upon the top of the sections 1^a and 1^b. In this position all of the parts are folded so as to make a compact device and the free ends of the bracing legs 23', the only parts exposed beyond the square outline of the package, are supported upon the brackets 25 or in any other suitable manner.

15 What is claimed is:—

15 In a curtain stretcher, a two-part extensible dove-tailed adjustable brace, side members pivoted to one part of said brace and arranged to fold thereon, said side members comprising extensible dove-tailed sections 20 arranged to aline with each other, means for holding the sections in adjacent relation with respect to one another, a block connected to the other part of said brace and having its upper surface arranged flush 25 with the upper surface of the side members,

second side members pivoted to the other end of said brace and comprising dove-tailed extensible sections arranged to aline with each other, end members comprising adjustable sections, one of which is pivoted to one of the sections of the second named side members and the other of which is arranged to engage one of the second named side members, bracing legs pivoted to and arranged to fold upon the end members, said second side members arranged to fold upon the first side members, and said end members arranged to fold upon the second side members, hooks carried by the sections of the side and end members, and a locking pawl carried by one part of said brace and adapted to engage in apertures formed in the other part of said brace for holding the brace in adjusted position.

30 In testimony whereof I affix my signature in presence of two witnesses.

STANLEY ROKOSZ.
